CROP DRYER

Raymond Sanders and Norman H. Sanders, Jr., both of
R.D. 1, Greenwich Township, Huron County, Ohio
44839

Filed Aug. 31, 1966, Ser. No. 3,671

Term of patent 14 years

(Cl. D13—1)

The figure is a perspective view of a crop dryer embodying the design of my invention.

The end elevation of the crop dryer, which is not shown, is substantially the same as the opposite end elevation shown; but with all blower, heater and controlling elements omitted.

The lateral elevation, not shown, is substantially the same as that shown in the drawing.

I claim:

The ornamental design for a crop dryer, substantially as shown and described.
